UNITED STATES PATENT OFFICE

2,602,218

DOUBLE-ACTION CAN OPENER AND
BOTTLE CAP REMOVER

Herman Schmitt, Sheboygan, Wis.

Application January 23, 1948, Serial No. 3,894

1 Claim. (Cl. 30—16)

1

This invention relates to a device for opening liquid containers, and the primary object of this invention is to provide a device of this character that possesses triple opening action for the containers, as well as a jar cap and crown cap removing action.

Another object of the invention is to provide a device of this character that is provided with a double piercing blade on an elongated handle, thereby providing a choice of two cutting blades suitable for forming an inwardly turned pouring spout for liquid containers.

A further object of the invention is to provide a device of this character, having two separate piercing blades that are adapted to punch a large U-shaped opening or a narrow elongated opening in a liquid container.

A further object of the invention is to provide an elongated handled device of the character described, that is provided with two cutting blades at one end of the handle and a jaw cap lifter at the other end of the handle.

With the above and other objects and advantages in view, the invention consists of the novel details of construction, arrangement and combination of parts more fully hereinafter described, claimed and illustrated in the accompanying drawings in which:

Figure 1 is an edge view of one form of the invention;

Figure 2 is a face view of the form shown in Figure 1;

Figure 3 is an edge view of another form of the invention;

Figure 4 is a face view of the form shown in Figure 3;

Figure 5 is a top plan view of the form shown in Figures 3 and 4;

Figure 6 is a sectional view on the line 6—6 of Figure 4;

Figure 7 is an edge view of another form of the invention;

Figure 8 is a face view of the form shown in Figure 7;

Figure 9 is an elevational view of the form shown in Figures 7 and 8, in the act of punching a hole in a liquid container;

Figure 10 is an elevational view of the form shown in Figures 7 and 8 in the act of punching a hole in a liquid container;

Figure 11 is a detailed view of the form shown in Figures 3 and 4, in the act of opening a jar cap and

Figure 12 is a detailed face view, showing the

2

manner of operation of the form shown in Figure 11.

Referring more in detail to the drawings and more especially to Figures 1 and 2, the opener embodying this form of the invention is designated by the reference numeral 10. The opener 10 is made of a strip of rigid metal, bent on itself at one end to form the circular hand grip or pressing knob 11.

10 The opposite end of the opener has a small piercing blade 12 and a large piercing blade 13, the blades 12 and 13 being separated by the guide projection 14 formed centrally of the blades 12 and 13 respectively.

15 The cutters 12 and 13 are formed at the longitudinal edges of the opener 10, and the portion 14 of the opener 10 forming the blades is of a larger diameter than the remainder of the opener.

20 Struck out from the portion 14, adjacent its upper end, is an irregular shaped cutting blade 15, which will punch a larger opening in the liquid container than will the blades 12 and 13. Below the knob 11, an opening 16 is provided, whereby 25 the opener can be supported from a nail or hook, as desired.

In Figures 3 to 6, inclusive, and in Figures 11 and 12, there is shown another form of the invention embodying an opener 20.

30 The opener 20 is also formed from a rigid strip of metal bent at right angles at one end to form the jar lid wrench or remover 21.

As shown in Figures 11 and 12, the wrench is placed in the gap between the lid 22 and the rib 35 23 on the jar 24, and when moved in either direction, as shown by the arrows, in Figure 12, the wrench will remove the lid 22 from the jar.

Below the wrench, the opener is provided with 40 an elongated slot 25, which is used for supporting the opener. Below the slot 25, an irregular cutter 26 is struck out from the opener, and this cutter is of the same form as the cutter 15 of the opener 10.

45 At the lower end, the opener is provided with a small cutter 27, and a cutout or jaw 28, which can be used for removing crown caps from bottles. Adjacent the cutter 27, the opening is provided with a guide or pry 29, which is used 50 to open small cans or the like.

In Figures 7 to 10, inclusive, the form of the opener 30 shown, is also made from a rigid strip of metal, the opener being bent upon itself at one end to form the circular hand grip or pressing knob 31. Below the knob 31, the opener has

the opening 32 whereby the opener may be hung up as desired.

At the lower end, the opener has the cutter blade 33 spaced from the guide 34, and above the blade 33, the irregular shaped cutter 35 is punched out of the opener.

In Figure 9, the cutter 35 is punched a substantially U-shaped opening 36 in the container 37, while in Figure 10, the cutter 33 is punching an elongated opening 38 in the container 37.

In all forms of the invention, the cutters are placed in the container, and a hole is punched by a downward pressure on the upper end of the opener.

As shown in Figures 9 and 10, the punched out portion 39 of the container 37 is crimped or pressed tightly against the inner wall of the container, so that this portion interferes in no way with the liquid as it is poured from the can.

The cutters will punch holes of various sizes, depending upon the desires of the users thereof. In all instances, the cutters crimp the punched out portion of the container, and it is believed that from the foregoing description, the structure of the various forms, as well as their operation, will be apparent to those skilled in the art.

It is also to be understood that changes in the minor details of construction, arrangement and combination of parts may be resorted to, provided they fall within the spirit of the invention and scope of the appended claim.

Having thus described the invention, what is

claimed as new and desired to be secured by Letters Patent is:

As a new article of manufacture, a utensil fabricated of a single piece of rigid material shaped to define a flat shank, a cutter arranged intermediate the ends of said shank and including a first portion extending angularly from said shank, a second portion extending from said first portion and arranged in spaced parallel relation with respect to the longitudinal axis of said shank, and a third portion extending outwardly from said second portion and arranged substantially parallel to said first portion, the outer end of said third portion being pointed and provided with a sharp beveled cutting edge, said cutter being struck out from said shank.

HERMAN SCHMITT.
